HARVEY P. SLEEPER, OF NEWARK, NEW JERSEY, AND CHARLES LE G. FORTESCUE, OF PITTSBURGH, PENNSYLVANIA, ASSIGNORS TO WESTINGHOUSE ELECTRIC AND MANUFACTURING COMPANY, A CORPORATION OF PENNSYLVANIA.

PHASE-SEQUENCE RELAY.

Application filed January 8, 1924, Serial No. 685,060. Renewed May 9, 1929.

Our invention relates to electrical protective devices and more particularly to phase-sequence relays.

One object of our invention is to provide 5 a phase-sequence relay that shall be adapted to protect a polyphase circuit under conditions of overload or short-circuit, phase unbalance, open-phase and phase reversal.

Another object of our invention is to provide 10 a time element relay that shall operate only in response to the positive or negative phase-sequence component of the currents in a polyphase circuit.

Still another object of our invention is to provide 15 a unitary relay that shall combine the functions formerly secured only by the employment of a plurality of separate relay structures.

A further object of our invention is to provide 20 a relay of improved construction that distinguishes between positive and negative phase-sequence components of current.

Heretofore, it has been necessary to provide 25 relays in each phase of a polyphase circuit in order to protect the circuit against conditions of overload and short-circuit, phase-reversal, open phase or phase unbalance. Such instruments are expensive and the number of such instruments required to adequately protect 30 any polyphase circuit from the many interruptions to service to which such lines are subjected, is excessive. With our improved relay, the above enumerated protective features are obtained by the use of a single instrument that operates in response to an abnormal positive phase-sequence component or negative phase-sequence component of current caused by a fault, irrespective of the 35 phase or phases involved in the fault.

In our relay, an impedance network is 40 provided of such character that two branches thereof are traversed by currents proportional to the positive and the negative phase-sequence components of the currents in the 45 phase conductors of an associated polyphase circuit under all conditions. A relay is connected in each of the respective branches of the network and is energized in accordance with the magnitude of the corresponding 50 symmetrical component, the positive phase-sequence component being a measure of the overload and the negative phase-sequence

component being a measure of the unbalance of the circuit.

In the several figures of the drawings, 55 Figure 1 is a front elevational view of a relay embodying our invention.

Fig. 2 is a side view, partially in elevation and partially in section, of the relay shown in Fig. 1.

Fig. 3 is a sectional view taken along the line III—III of Fig. 2.

Fig. 4 is a diagrammatic view of apparatus and circuits embodying our invention.

Fig. 5 is a diagrammatic view of a different 65 arrangement of circuits and apparatus.

Fig. 6 is a vector diagram of the currents traversing our relay under normal condition of phase balance.

Figs. 7 and 8 are vector diagrams of the 70 currents traversing our relay under conditions of phase reversal.

Figs. 9 to 11, inclusive, are vector diagrams of the currents traversing our relay under conditions of open phase.

Fig. 12 is a vector diagram of a three-phase unbalance; and

Fig. 13 is a diagrammatic view of circuits and apparatus showing our relay used in combination with a grounded polyphase 80 circuit.

Referring to Fig. 4, our invention comprises, in general, a unitary relay structure 10 that embodies a resistor 11, reactors 12 and 13, and the winding 14 of a relay. These 85 parts are connected in an impedance network or bridge, the several junctions of which are connected to current transformers 16 and 17 in a polyphase circuit 18.

The current traversing the resistor 11 is 90 in phase with the applied voltage and the reactance and resistance of the reactor 13 is such as to cause the current traversing the same to lag the applied voltage by sixty degrees. The resistance and reactance of 95 the reactor 12 and the windings of the relay 14 are equal. The reactor 12 may take the form of a winding 15 of a second relay, as shown in Fig. 5. The relays comprising the windings 14 and 15 may be connected to a 100 suitable circuit interrupter or other electrical devices (not shown) for controlling the polyphase circuit 18.

Referring to Figs. 1 and 2, the relay com-

prises a base member 21 that is provided with a plurality of lugs 22 that serve both as supports and electrical terminal members. A cover 23 is secured to the base member 21 by suitable wing nuts 24.

The reactors 12 and 13 are mounted at the opposite upper corners of the base member 21. Between them are disposed a plurality of spools having coils thereon constituting the resistor 11. On the lower half of the base 21 is mounted a relay 25 that comprises the winding 14, a pivoted armature member 19 controlled thereby a stationary contact member 27 and a movable contact member 28 secured to the armature member 19 and controlled by the current traversing the winding 14. Damping magnets 20 are provided for retarding the movement of the armature member 19. The relay 25 is of the overload induction type having an inverse or definite time-element characteristic and since its functions and details of operation are well known in the art, a description thereof is believed to be unnecessary, except in so far as it is necessary to complete the combination with the remaining component parts of my invention.

Referring to Figs. 4 and 6, under conditions of current balance in the circuit 18, the currents traversing the several phases A, B and C are normally 120 degrees apart. The current from the current transformer 16 that is connected in phase A is delivered to the impedance network between the arms 11, 12 and 13, 14, while the current from the current transformer 17, that is connected in phase B, is delivered to the impedance network between the arms 11, 14 and 12, 13. No current transformer is placed in the phase C for the reason that any disturbance between phase C and either of the other phases A or B will be recorded by an unbalance in the affected phases.

Under balanced conditions, the current from the phase A traverses the parallel circuits comprising resistor 11 and winding 14, and reactor 12 and reactor 13. By reason of the relation of the resistor 11 to the resistance and reactance of the reactor 13, which is of the same absolute impedance, a current proportional to the positive phase-sequence component traverses the reactor 12 and a current proportional to the negative phase-sequence component traverses the relay winding 14. As is shown in Fig. 5, the fact that both positive and negative phase-sequence components traverse the network may be taken advantage of by having the reactor 12 comprise the winding 15 of a second relay 26 responsive to the magnitude of the positive phase-sequence component, thereby providing overload and short-circuit protection to the circuit 18.

Referring to Fig. 6, the currents A_{12} and B_{12} derived from phases A and B are nor-

mally equal in amount and opposite in direction under balanced conditions, thereby equalizing one another with the result that no current traverses the winding 14 of the relay 25. Under unbalanced conditions, a current proportional to the negative phase-sequence component traverses said winding.

As shown in Fig. 4, the current A_{12} lags the current A_{14} by an angle of 60° under balanced conditions because of the greater reactance of the branch 13 with respect to the branch 11 of the network. The sum of the currents A_{12} and A_{14} is equal to the current in the phase conductor A (see Fig. 6). In a similar manner, the current B_{12} lead the current B_{14} by an angle of 60° under balanced conditions and the sum of the currents B_{12} and B_{14} is equal to the current in the phase conductor B.

Consequently, by reason of the vector relation of A_{12} , B_{12} , A_{14} and B_{14} , as shown in Fig. 6, the sum of the currents A_{12} and B_{12} , which traverses the branch 12 of the network, is proportional under all conditions to the positive phase-sequence component of the currents in the distribution circuit and the sum of the currents A_{14} and B_{14} , which traverses the branch 14 of the network, is proportional to negative phase-sequence component. Under balanced current conditions, which are shown in Fig. 6, the positive component is a maximum and the negative component is zero. Various other conditions are illustrated in Figs. 7 to 12.

Referring to Fig. 7, upon the occurrence of a reversal between the phases A and B, the currents A_{12} and B_{12} are substantially equal and opposite in direction with the result that substantially no current traverses the reactor 12 while the sum of the currents A_{14} and B_{14} traversing the winding 14 becomes of an appreciable value with the result that the relay 25 is operated to control any desired mechanism connected with the circuit 18, such as a circuit interrupter (not shown).

Similarly, upon the reversal of phases B and C, the positive phase-sequence components of current become effective to operate the negative phase-sequence relay 25. By comparing Figs. 7 and 8, it will be seen that the vector diagrams are identical except for the fact that the relatively angular displacement of similar components is different.

Referring to Fig. 9, there is shown a vector diagram of the current traversing the relay when phase C is open. In this case, the currents A and B are equal and opposite in direction and a negative phase-sequence component exists which operates the relay 25.

The circuit conditions, when phases A and B are open, are shown in Figs. 10 and 11. In either event, a negative phase-sequence current of an appreciable value traverses the winding 14 of the relay 25 that is operated.

Referring to Fig. 12, a condition of three-

phase unbalance is shown wherein the currents A, B and C are displaced at other than 120 degrees. It will thus be seen that the resulting negative phase-sequence current 14 5 has an appreciable value and, therefore, operates the relay 25.

Referring to Fig. 13, if the phase-sequence relay is to operate on a distributing system having a neutral point grounded as at 31 and 10 32, it may be undesirable to have it influenced by the zero phase-sequence component of current, in which case the disposition of the current transformers may be such as to eliminate the zero phase-sequence component from the 15 circuits of the relay. This result is secured by providing the current transformers 33 and 34, corresponding to the relays 16 and 17, of Fig. 4, respectively, with two primary windings 35, 36, 37 and 38, respectively.

20 Winding 35 is connected directly in phase A and the associated winding 36 is connected in reverse direction in phase B. The primary winding 37 of the transformer 34 is connected directly in phase C and the winding 38 thereof is connected reversely in phase B. The secondary windings of current transformers 33 and 34 are traversed by currents proportional to the positive and negative phase-sequence currents in the power circuit, 30 but the zero phase-sequence component is eliminated therein. The relay is thereby rendered independent of current in the grounded circuit which is the zero phase-sequence current and provision is made for protection 35 against grounds by interposing a suitable instrument 39 in the grounding lead for operating on a predetermined value of ground current.

It will thus be seen that we have provided 40 a relay that is responsive to the value of the positive and negative phase-sequence currents in the polyphase circuit. We have also provided a single unitary relay that is responsive to any fault that produces an unbalanced current condition, irrespective of 45 the phase or phases affected thereby. Since the positive phase-sequence current is a measure of the overload or short-circuit conditions in the circuit and since the negative phase-sequence current is a measure of phase unbalance, phase reversal and open-phase conditions, two relays embodying our invention 50 will afford all the desired protection for a polyphase electrical circuit. One of the advantages of our invention, as will appear, 55 is that a great saving in the use of current transformers, as well as of relays, is effected while still obtaining complete circuit protection.

60 Furthermore, the negative phase-sequence relay with a time-element or retarded operation has an important application in large distribution systems in which the unbalance of the system currents upon the occurrence of 65 a fault is greater in certain portions of the

system than in other portions. Since the degree of energization of the relay depends upon the magnitude of the negative phase-sequence quantity or, in other words, upon the amount of unbalance of the system, the time of operation of the relay varies in accordance with its relation to the fault. In this manner, selective disconnection of the faulty portion of the distribution system may be obtained.

We do not wish to be restricted to the specific circuit connections or arrangement of parts herein set forth, as various modifications thereof may be effected without departing from the spirit and scope of our invention. We desire, therefore, that only such limitations shall be imposed as are indicated in the appended claims.

We claim as our invention:

1. An electrical protective device comprising an impedance network consisting of a winding of a relay, a resistor and a pair of reactors, one of said reactors having the same resistance and reactance as the winding of the relay.

2. An electrical protective device comprising a quadrilateral impedance network consisting of a winding of a relay, a resistor and a pair of reactors, one of said reactors having the same resistance and reactance as the winding of the relay, being disposed on an opposite side of the impedance network relative to the winding of the relay.

3. An electrical protective device comprising a quadrilateral impedance network consisting of a winding of a relay, a resistor, and a pair of reactors, one of said reactors having the same resistance and reactance as the winding of the relay, and being disposed on an opposite side of the impedance network relative to the winding of the relay, said reactor constituting an element of a second relay.

4. The combination with a polyphase electrical circuit, a relay and a plurality of transformers connected to said circuit, of an electrical protective device comprising a quadrilateral impedance network energized from said transformers comprising a winding of the relay, a resistor and a pair of reactors, the winding of said relay and a reactor of equal resistance and reactance constituting opposite sides of the impedance network.

5. The combination with a polyphase electrical circuit, a relay and a plurality of transformers connected to said circuit, of an electrical protective device comprising an impedance network in the form of a bridge having opposite points connected to each of the respective transformers consisting of a winding of the relay, a resistor and a pair of reactors, the winding of said relay and a reactor of equal resistance and reactance constituting opposite arms of the impedance network, whereby said relay is caused to operate only in response to one phase-sequence component of the current in the polyphase circuit.

6. The combination with a polyphase electrical circuit, a relay and two transformers connected in separate phases of said circuit, of an electrical protective device comprising 65
 5 an impedance bridge network energized from said transformers consisting of a winding of the relay, a resistor and a pair of reactors, the winding of said relay and a reactor of equal resistance and reactance constituting 70
 10 opposite arms of the impedance network whereby the relay is caused to operate in accordance with the negative-phase-sequence 75
 component of the current traversing the circuit which is a measure of the conditions of 15
 15 open phase, phase unbalance, unsymmetrical short circuit, and phase reversal in said circuit.
7. The combination with a polyphase electrical circuit, a relay and a plurality of transformers connected to said circuit, of an electrical protective device comprising a quadrilateral impedance network energized from 80
 20 said transformers consisting of a winding of the relay, a resistor and a pair of reactors, the 25
 winding of said relay and a reactor of equal 30
 resistance and reactance constituting opposite arms of the impedance network and the resistor and other reactor constituting the other arms of the network and having such 35
 30 relative characteristics that the relay is caused to operate under conditions of phase unbalance in said circuit.
8. The combination with a polyphase electrical circuit, a relay and two transformers 35
 35 connected to separate phases of said circuit, of an electrical protective device comprising an impedance bridge network having opposite points connected to each of the respective 40
 40 transformers consisting of a winding of the relay, a resistor and a pair of reactors, the 45
 winding of said relay and a reactor of equal 50
 resistance and reactance constituting opposite arms of the impedance network and the resistor and the other reactor constituting the other arms of the network and having such 55
 55 relative characteristics that the relay is caused to operate under open-phase conditions in said circuit.
9. The combination with a polyphase electrical circuit, a relay and two transformers connected to separate phases of said circuit, of an electrical protective device comprising an impedance bridge network having opposite points connected to each of the respective 60
 60 transformers, a winding of the relay forming one of the branches of said network.
10. The combination with a polyphase electrical circuit, a plurality of connected transformers, and a pair of relays, of an impedance network energized from said transformers consisting of a resistor, a reactor and a winding of each of said relays, whereby said network causes the operation of one of said relays upon the occurrence of negative phase- 65
 65 sequence currents in said circuit and said network causes the operation of the other relay under conditions of excessive positive phase- 70
 sequence currents in said circuit. 75
 11. The combination with a polyphase electrical circuit, a relay and a plurality of transformers connected to said circuit, of an electrical protective device comprising an impedance network energized from said transformers consisting of a winding of the relay, a resistor and a pair of reactors, the winding of said relay and a reactor of equal resistance and reactance constituting opposite arms of the impedance network whereby said relay is caused to operate only in response to negative phase-sequence currents in the polyphase circuit. 80
12. An electrical protective device comprising an impedance bridge network, one of the branches of which contains a member operable in response to negative phase-sequence currents and another branch a member operative in response to positive phase-sequence currents. 85
13. An electrical protective device comprising an impedance bridge network for segregating negative phase-sequence currents from positive phase-sequence currents and means for selectively responding to currents of a predetermined phase sequence. 90
14. An electrical device comprising a quadrilateral bridge network responsive to both positive and negative sequence currents independent of sequence voltages for segregating the negative sequence currents from the positive sequence currents, and means selectively responsive to currents of predetermined phase sequence for influencing another electrical device. 95
15. The combination with a polyphase electrical circuit, a pair of relays, means, comprising a plurality of current transformers, for eliminating zero sequence currents from the pair of relays, of another relay responsive to zero sequence currents alone, and an impedance bridge network energized from the 100
 100 transformiers consisting of a resistor, a reactor and a winding of each of said pair of relays, whereby said bridge network causes the operation of one of said pair of relays upon the occurrence of negative sequence currents in 105
 105 said circuit and said bridge network causes the operation of the other of said pair of relays in response to excess positive sequence currents in said circuit. 110
16. The combination with a polyphase electrical circuit, of means for separating out or segregating both the positive and the negative sequence currents from the zero sequence currents in the circuit, means responsive to the last-named means and comprising a quadrilateral bridge network for segregating the negative sequence currents from the positive sequence currents, and means selectively and 120
 120
- 125

separately responsive to predetermined sequence currents for influencing another electrical device.

17. In combination with an electrical circuit having a circuit interrupter therein, of means for controlling the operation of said interrupter including means responsive to

phase-sequence quantities of said circuit, and means for eliminating the zero phase-sequence quantities from said control means. 10

In testimony whereof, we have hereunto subscribed our names.

HARVEY P. SLEEPER.
